UNITED STATES PATENT OFFICE.

THOMAS WARD, OF LUBEC, MAINE, ASSIGNOR TO AMERICAN CAN COMPANY, OF NEW YORK, N. Y., A CORPORATION OF NEW JERSEY.

ALTERNATING FEEDING MECHANISM.

1,158,088.

Specification of Letters Patent. Patented Oct. 26, 1915.

Application filed December 2, 1912. Serial No. 734,430.

To all whom it may concern:

Be it known that I, THOMAS WARD, a subject of the Kingdom of Great Britain, residing in Lubec, in the county of Washington 5 and State of Maine, have invented a new and useful Improvement in Alternating Feeding Mechanism, of which the following is a specification.

This invention relates to improved mechanism for feeding articles, such as sardine cans, alternately from two chutes into a single, common chute.

In the manufacture of seamless drawn cans, such as sardine cans, the drawing operation leaves the cans with an irregular, rough edge which subsequently must be cut or trimmed in a trimming press, to insure that all the cans are of the proper size, and in practice, it is found that a trimming press 20 has approximately double the capacity of a drawing press, so that for every two drawing presses only one trimming press is required to handle the output.

One object of this invention is to provide 25 a mechanism which will govern the feed of cans, as they pass from the drawing presses to the trimming press, in such a way that the rough drawn cans as they come from two drawing presses along two chutes, will 30 be fed alternately from these two chutes into a single common chute that conducts the cans to a trimming press, to thereby obtain the maximum efficiency in operating the drawing and trimming presses.

Another object of the invention is to provide 35 a feeding mechanism for cans or other articles, which will automatically stop feeding the cans or be rendered inoperative, whenever a jam occurs, or any abnormal 40 resistance is encountered in propelling the cans.

In the drawing forming a part of this 45 specification, Figure 1 is a front elevation of a device embodying my improvements, a part of the structure at the bottom thereof being shown in section to more clearly illustrate the arrangement. Fig. 2 is a side elevation of the structure illustrated in Fig. 1, and Figs. 3 and 4 are vertical and horizontal 50 sectional views, taken respectively on the lines 3—3 and 4—4 of Fig. 2.

As shown in the drawing, the feeding 55 mechanism comprises a main cast member 10, having outer walls 11 and an inner, central rib 12 at the upper portion thereof, forming a pair of parallelly arranged guide-

ways or chutes down which sardine cans 13 are adapted to pass as the same are fed from two drawing presses, (not shown), down the chutes 14, 14. At the lower portion of 60 the member 10, the outer walls 11 are converged, as shown at 15, to thereby form a single passageway or chute common to the upper pair of chutes, and which leads to the trimming press. Secured to the lower end 65 of the rib 12 is a spring-arm 16, adapted to prevent the sardine cans from becoming twisted as the same are fed from the upper chutes to the third or common lower chute, and a plurality of plates 17 are secured to 70 the member 10, which project over the outer walls 11 and rib 12 to retain the cans in proper position in the chutes. Over the entrance to the lower common chute, and above the converging portions 15, is placed a pivoted member 18, having spaced arms 19, 19, and held in normal position by means of a 75 spring 20.

As the cans fall down the upper pair of 80 chutes under the influence of gravity, the same are held temporarily by detents in the form of leaf springs 21 that project through slots 22 in the side walls 11 and engage the cans, whereby the cans are prevented from jamming in the feed mechanism. The cans 85 are propelled in the chutes by means of a plurality of feed fingers 23 in the form of spokes secured to a rotatable shaft 24, mounted in bearings 25, carried by supporting rods 26 slidably mounted in guide posts 27 formed 90 integral with the main member 10. The shaft 24 with the feed fingers thereon is reciprocated by means of a rod 28, pivotally connected to the shaft and operated by a movable part of the trimming press by means 95 of a bar 29, adjustably secured to the rod 28 by means of a nut and thread connection, as shown at 30, whereby the path of travel of the reciprocating shaft may be regulated. The shaft 24 is threaded at one end, as shown 100 at 31, and adjustably mounted thereon is a nut 32, adapted to regulate the compression of a coiled spring 33 mounted on the shaft 24 between the nut 32 and a washer 34. Mounted between the washer 34 and the adjustable bearing 25 is a fiber washer 35. On the opposite side of the bearing member 25 is mounted another fiber washer 35, held in position by means of a collar 36, secured to the shaft 24, as by means of a set screw 37. 105

By means of the washers, coiled spring and nut arrangement above described, the 110

amount of friction tending to prevent the shaft 24 from rotating, may be varied and adjusted at will, for the purpose hereinafter described.

5 The feed fingers 23, as clearly shown in the drawings, are angularly offset from each other ninety degrees, so that when one of them is in position to engage a can in one chute, the other will be in an inoperative position, and in order to alternate the positions of these feed pins 23, the shaft has secured thereto at its end a hub 38, having four turning fingers 39 thereon which are adapted to be operated during the upstroke 10 of the shaft by means of a spring-controlled pawl or trip 40 which, as will be obvious, allows the turning pins to pass thereby on the downstroke, but will engage the latter and thereby rotate the shaft a quarter turn 15 on the upstroke. The trip 40 is pivotally mounted on a pin 41, secured to a bracket 42, the latter being secured to the body member 10. Also mounted on the member 10 at a point below the pawl or trip 40 is a shorter 20 spring-controlled pawl or trip 43, the function of which is to insure the proper positioning of the turning pins 39 for engagement with the upper pawl or trip 40, and preventing the ends of the turning pins 25 from striking directly against the upper pawl or trip 40.

The operation of the device is as follows: On the downstroke of the shaft 24, one of 30 the feed pins will engage the inside of a can at the lower end thereof (see Fig. 3), and will pull the same by the detent 21, whereupon the can, under the influence of gravity 35 will fall down the chute until the upper end of the can engages the pin. The can is then carried back by the pin on the upstroke, until 40 one of the turning pins 39 is engaged by the trip 40, which will rotate the feed pin a sufficient amount to release the can, which will then fall, under the influence of gravity, 45 down into the lower chute and thence to the trimming press. As the feed pin in one of the upper chutes is turned so as to release a can held by it, the feed pin in the adjacent chute will be brought into operative position 50 to engage a can in that chute, and upon the next downward stroke of the shaft, the foregoing operation will be repeated, thus feeding the cans alternately from the pair of chutes to the single chute leading to the 55 trimming press. If, at any time, an abnormal resistance is encountered in propelling a can, the feed pin in engagement therewith will yield, due to the frictional washer arrangement on the shaft 24, a sufficient 60 amount to pass over the edge of the can, thereby preventing damage to any of the parts.

Although I have herein described what I now consider the preferred form of my invention, yet I am aware that various changes

and modifications may be made in the parts and details of construction without departing from the spirit of the invention, and all such changes and modifications are contemplated as come within the scope of the claims 70 appended hereto.

It will also be apparent that my improvements may be adapted for feeding articles from more than two chutes into a single common chute, by duplicating the feed fingers 75 for each additional chute and arranging the turning fingers at the end of the shaft to correspond with the number of chutes, and, if desirable, the turning fingers 80 may be so arranged and operated that articles will be fed from one chute into the common chute at a greater or less rate than they are fed from another of the chutes, that is to say, in the case where there are two 85 chutes merging into a single common chute, as shown in the structure in the drawing, the cans may be fed at the rate of two cans from one chute to one can from the other chute.

I claim:—

1. A feeding apparatus of the character described comprising, in combination: a plurality of chutes arranged side by side and all leading to a common chute; means for feeding articles successively from each one 90 of the plurality of chutes to the common chute, said means including feed fingers for each of said chutes, all of said fingers being connected and moving longitudinally of the chute together and being differently 95 arranged for the different chutes, so that when those adapted to propel articles in one of said plurality of chutes are in operative position, those adapted to propel articles in the other of the plurality of chutes are 100 in inoperative position; whereby the accurate alternate feeding of articles is effected.

2. A feeding apparatus of the character described comprising, in combination: a plurality of chutes all leading to a common 110 chute; and reciprocating means for feeding articles successively, and in rotation from each of said plurality of chutes to the common chute, said means including a rotatable shaft having feed fingers thereon, some of 115 which are adapted to propel articles in one chute and the others of which are adapted to propel articles in other of said plurality of chutes, said feed fingers being angularly offset from each other and the fingers of one 120 chute being connected with the fingers of the other chute by said shaft.

3. A feeding apparatus of the character described comprising, in combination: a pair 125 of chutes arranged side by side down which articles are adapted to feed by gravity, said chutes leading to a common third chute; yieldable detents, in the first named chutes, adapted to temporarily arrest articles as the same pass therethrough; and means for 130

feeding articles with accurate alternation and in a direction parallel with the pair of chutes, from the latter to the third chute, substantially as specified.

5 4. A feeding apparatus of the character described comprising, in combination: a pair of chutes arranged side by side down which articles are adapted to feed by gravity, said chutes merging into a common third chute; 10 detents in said first named chutes adapted to arrest articles as the same pass therethrough; and combined reciprocating and rotary means for feeding articles in a direction parallel to the pair of chutes from the 15 latter to the common third chute, substantially as specified.

5. A feeding apparatus of the character described comprising, in combination: a pair of chutes arranged side by side; a common 20 third chute to which the pair of chutes deliver; and means for feeding articles alternately from said pair of chutes to the third chute, said means including a plurality of feed fingers connected and arranged so that 25 the positioning of the fingers of one chute is accompanied by a different positioning of the connected fingers of the other chute, and when those adapted to propel articles in one of the pair of chutes are in operative position, those adapted to propel articles in the other of the pair of chutes are in inoperative position, substantially as specified.

6. A feeding apparatus of the character described comprising, in combination: two 35 guide-ways along which articles are adapted to be fed, the same merging into a common guideway; a movable feeding element adapted to engage articles in said two guideways alternately and propel the same toward said 40 common guide-way; power mechanism for actuating said element; and adjustable frictional devices adapted to permit the power mechanism to operate while the engaging end of said element remains immovable when 45 more than a predetermined amount of resistance is encountered in propelling an article along one of said guide-ways; substantially as specified.

7. A feeding apparatus of the character 50 described, comprising, in combination: a pair of chutes arranged side by side and merging into a common third chute; and reciprocating means for feeding articles alternately from the pair of chutes to the common third 55 chute, said means including a rotatable shaft having feed fingers thereon, some of which are adapted to propel articles in one chute, and the others of which are adapted to propel articles in the other chute, said feed 60 fingers being angularly offset from each other, whereby the articles are fed on alternate strokes, substantially as specified.

8. A feeding apparatus of the character

described comprising, in combination: a pair of guide-ways arranged side by side and 65 merging into a common third guide-way; a bodily reciprocal, rotating shaft having feed fingers thereon angularly offset and adapted to propel articles in the pair of guide-ways; turning pins secured to said shaft and adapted 70 to rotate the latter; a trip for operating said turning pins; and frictional means yieldingly preventing said shaft from rotation while the feed fingers thereon are propelling articles in the guide-ways, substantially 75 as specified.

9. A feeding apparatus of the character described comprising, in combination: a pair of chutes arranged side by side down which articles are adapted to feed by gravity, said 80 chutes merging into a common third chute; a yieldable detent in each of said first named chutes adapted to arrest articles in their passage through the chutes; a bodily reciprocal, rotatable shaft, having angularly arranged 85 feed fingers secured thereto and disposed over said pair of chutes; means for rotating said shaft during its bodily reciprocating movement; and an adjustable, frictional device for yieldingly preventing said shaft 90 from rotation, substantially as specified.

10. In an apparatus for feeding cans, in combination: can delivering chutes arranged side by side; a receiving chute communicating with and adapted to receive cans from each of the said delivering chutes; a rotary finger for each delivering chute each adapted to propel cans in its chute, the several fingers being connected and turnable together; a power device for reciprocating bodily the 100 fingers lengthwise of the delivery chutes; detents for temporarily holding the cans in the delivery chutes until they are propelled by the fingers; means for giving all of the fingers a partial turn at each bodily reciprocation; and a frictional yielding connection between the fingers and their actuating means. 105

11. In a can-feeding apparatus, in combination: a chute along which the cans are caused to pass; a detent for arresting the cans at a predetermined point; a feeding finger for causing the cans to be fed past the said detent successively; a power device for actuating the said finger to give it a feeding movement; and yielding power-transmitting means between the power device and the finger, arranged to have force enough to overcome the resistance of the detent and to feed the cans, and to yield and permit the operation of the power device without the feed 120 operation of the finger in case the cans are otherwise arrested in the chute. 110 115

THOMAS WARD.
